(57) **ABSTRACT**

A new distinct variety of grapevine named 'ARDFORTYONE' abundantly forms attractive meaty seedless berries with a black skin coloration, lax small clusters which display a natural flavor, the fruit commonly is ready for harvesting during June in San Joaquin Valley of Central California, U.S.A, and displays good eating qualities as a table grape as the fruit firmness renders the fruit well amenable for handling, shipping, and storage.

1 Drawing Sheet

1

Classification: The present invention relates to a new *Vitis vinifera* Grapevine.

Variety denomination: The new Grapevine has a varietal denomination 'ARDFORTYONE'.

BACKGROUND OF THE INVENTION

A breeding program was initiated during the late 1990's near Bakersfield in San Joaquin Valley of Central California. In 2013, during this breeding program, a new variety of *Vitis vinifera* was created by deliberate cross breeding of two parent plants by emasculation of the pollen bearing organ of the female and introducing pollen from another male origin. The female parent of the new variety was 8-7+7, which is a red natural sweet flavored variety with very good berry attachment (non-patented in the United States). The male parent (i.e. the pollen parent) of the new variety was 10-20+4, a black variety with large berries and a natural taste (non-patented in the United States).

TABLE 1

'ARDFORTYONE' compared with parents & closely related variety:				
	'ARDFORTYONE'	8-7+7	10-20+4	Summer Royal (non-patented)
Berry skin	Thin	Thin	Medium	Medium
Berry shape	Obtuse ovoid	Broad	Ovoid	Round - Oval
Cap stem/brush	Medium/Medium	Thin/Long	Medium/	Thin/Long
			Medium	

The parentage of the new variety can be summarized as follows:

8-7+7 X 10-20+4

2

An artificial pollination was created, and the result was an embryo which possessed unique genetic qualities. The rudiments resulting from the above pollination were embryo rescued.

In 2014 the plant was transplanted to Bakersfield in San Joaquin Valley of Central California.

It was found that the new grapevine of the present invention possesses the following combination of characteristics:

- (a) Forms attractive meaty seedless berries with a black skin coloration; in lax small clusters, which display a natural flavor,
- (b) Commonly bears fruit during the month of June in the San Joaquin Valley of Central California, U.S.A., and
- (c) Bears fruit that is firm and is well amenable for storage, handling, and shipping.
- (d) Produces 88 bunches per vine, and an average of about 2 bunches per shoot, at a total of 73 lbs. fruit per vine.

The new variety during observation to date has displayed no visible disease, and has displayed an ability to well resist cold, drought, heat; but sensitive to direct exposure to sun and wind. The fruit of the new variety has been found to display excellent handling and shipping qualities combined with desirable dessert eating qualities.

The new variety of the present invention has been found to undergo asexual propagation beginning in 2015 near Bakersfield in the San Joaquin Valley of Central California, U.S.A. by bud grafting on mature Thompson rootstock (non-patented in the United States). Such asexual propagation has been conducted thereafter in successive years to date and has shown that the characteristics of the new variety are strictly transmissible from one generation to another.

Accordingly, the new variety undergoes asexual propagation in a true to type manner.

SUMMARY OF THE INVENTION

The new variety 'ARDFORTYONE' is a black seedless table grape with a high production, e.g., about 88 bunches per vine, and an average of about 2 bunches per shoot.

Asexual reproduction by micro propagation of the new variety as performed near Bakersfield, Calif., U.S.A., shows that the forgoing and other distinguishing characteristics come true to form and are established and transmitted through succeeding propagations.

BRIEF DESCRIPTION OF THE DRAWING

The accompanying photographic illustration shows typical six-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

The drawing shows leaves, stems and grapes of ARD-FORTYONE.

DETAILED BOTANICAL DESCRIPTION

The chart used in the identification of colors is The R.H.S. Colour Chart of The ROYAL HORTICULTURAL SOCIETY (3rd Edition). The description is based on the observation of plants growing on 'Thompson Seedless' rootstock outdoors near San Joaquin Valley of Central California, U.S.A.

VINE CHARACTERISTICS:

vigor	Vigorous upright shoots
productive capacity	Bearing at a natural, average capacity. Spur pruning.
trunk	Strong and developed. Diameter is 3.7 inches, measured at 4.7 inches above ground. Rough with a fibrous, shaggy exterior. Light maple brown coloring (greyed orange 177C)

Date of bud burst in Bakersfield Calif.: February 23rd

YOUNG SHOOT CHARACTERISTICS:

Openness of tip	fully open
Density of prostrate hairs on tip	dense
Anthocyanin coloration of prostrate hairs on tip	none (yellow green 152A)

Density of erect hairs on tip

very dense

YOUNG LEAF CHARACTERISTICS:

Color of upper side of blade	yellow green 152A
Color of lower side of blade	yellow green 152B
Density of erect hairs between main veins on upper side of blade	absent or very sparse
Density of erect hairs between main veins on lower side of blade	absent or very sparse
Density of prostrate hairs on main veins on upper side of blade	absent or very sparse
Density of prostrate hairs on main veins on lower side of blade	medium

SHOOT CHARACTERISTICS:

5	Attitude (before tying)	erect
	Color of dorsal side of internodes	yellow green 144A
	Color of ventral side of internodes	yellow green 146B
	Color of dorsal side of nodes	yellow green 152A
	Color of ventral side of nodes	yellow green 144A
	Density of erect hairs on internodes	absent or very sparse
	Density of prostrate hairs on internodes	absent or very sparse
10	Length of tendrils	4.1 inches
	Diameter of tendrils	0.07 inches
	Color of tendrils	yellow green 152B
	Number of tendrils at bloom	3
	Positioning of first flowering and fruiting node	The first bunch is in the 3rd node
15	Inflorescence number per flowering shoot	2

FLOWER CHARACTERISTICS:

20	Reproductive organs developed gynoecium	Fully developed stamens and fully
	Flower length	0.33 inches
	Flower diameter	0.18 inches
	Pistil length	0.14 inches
	Pistil color	yellow green 144A
	Pollen Amount	rich
	Pollen color	yellow 8A
	Stamen color	yellow green 145C
	Stamen length	0.13 inches
30	Number of stamen	6

First bloom in Bakersfield, Calif.: April 28th

Date of full bloom in Bakersfield, Calif.: May 3rd

MATURE LEAF CHARACTERISTICS:

35	Size of blade	6.5 x 6.5 inches
	Shape of blade	wedge-shaped
	Base descriptors	pentagonal
40	Leaf margin	serrate
	Leaf apex	acute
	Blistering of upper side of blade	absent or very sparse
	Depth of upper lateral sinuses	shallow
	Number of lobes	five
	(Only varieties with lobed leaves)	closed
45	Arrangement of lobes of upper lateral sinuses	half open
	Arrangement of lobes of petiole sinus	0.46 inches
	Length of teeth	medium
	Ratio length/width of teeth	mixture of both sides straight and both sides convex
	Shape of teeth	absent or very sparse
50	Density of prostrate hairs between main veins on lower side of blade	absent or very sparse
	Density of erect hairs on main veins on lower side of blade	absent or very sparse
	Density of erect hairs between the main veins on upper side of blade	absent or very sparse
	Density of prostrate hairs on main veins on upper side of blade	absent or very sparse
	Length of petiole compared to length of middle vein	moderately longer
	Top side color	green 137A
55	Bottom side color	yellow green 146B
	Texture of upper side of blade	smooth
	Texture of lower side of blade	rough
	Vein color on upper blade	yellow green 146C
	Vein color on lower blade	yellow green 145C
	Venation pattern for upper blade	netlike venation
60	Venation pattern for lower blade	netlike venation

-continued

MATURE LEAF CHARACTERISTICS:	
Petiole length	6.35 inches
Petiole diameter	0.14 inches
Petiole color	yellow green 146D
Petiole texture	smooth

Date of beginning of berry ripening in Bakersfield Calif.:
May 28th

BUNCH CHARACTERISTICS:	
Size (peduncle excluded)	small
Density of berries on bunch	lax
Bunch length	6.5 inches
Bunch diameter	5.5 inches
Length of peduncle of primary bunch	5 inches
Diameter of peduncle of primary bunch	0.13 inches
Peduncle of primary bunch color	yellow green 152D
Peduncle texture	smooth
Bunches per vine	88
Average bunch weight	0.83lbs

BERRY CHARACTERISTICS:	
Size	small
Length	1 inch
Weight	0.2 oz
Diameter	0.78 inches
Shape	obtuse ovoid
Color of skin (without bloom)	black 202
Flesh color	greyed green 190D
Brix	17
Titratable acidity percentage	0.22%
Juice	4.25 pH
Ease of detachment from pedicel	moderately easy
Thickness of skin	medium
Anthocyanin coloration of flesh	none
Firmness of flesh	very firm
Particular flavor	none
Formation of seeds	rudimentary
Berries per bunch	91

PEDICEL CHARACTERISTICS:	
Length	0.3 inches
Diameter	0.06 inches
Color	yellow green 146C
Pedicel texture	rough

WOODY SHOOT CHARACTERISTICS:	
5	Woody shoot texture
	rough
	Woody shoot color
	greyed orange 166D
	Woody shoot length
	120 inches
	Diameter
	0.42 inches
	Internode length
	4.7 inches

Market use of observed plants: Fresh market

10 AGE AND GROWING CONDITIONS
Six years growing under Y system in South Joaquin Valley in hot, dry summers.

15 SHIPPING CHARACTERISTICS
Fruit was in cold storage. Stored in poly bags inside Styrofoam boxes with sulfur pads. After 60 Days: rachises were 75% green; 1% berry shattering; no berry wrinkling or cracks were apparent.

DNA PROFILE

To further characterize the new variety DNA was extracted from plant samples and a DNA profile was obtained at California Seed & Plant Lab, California USA using base pairs for 10 standard microsatellite DNA markers. The data is presented hereafter.

TABLE 2			
DNA profile for 'ARDFORTYONE'			
	Microsatellite DNA Marker	Allele Sizes in Base Pairs	
30	M1	232	240
	M2	239	249
	M3	179	194
	M4	212	212
	M5	251	273
	M6	133	145
	M7	189	201
	M8	255	257
	M9	212	212
	M10	237	247

45 The 'ARDFORTYONE' variety has not been observed under all possible environmental conditions to date. Accordingly, it is possible that the phenotypic expression may vary somewhat with changes in light intensity and duration, cultural practices, and other environmental conditions.

50 Additional information relating to plant and fruit disease and pest resistance or susceptibility has not been observed to date. Specification of the plant hardiness zone and the heat/cold resistance has not been observed to date.

55 What is claimed is:

1. A new and distinct grapevine, botanically known as *Vitis vinifera*, identified as 'ARDFORTYONE', substantially as shown and described herein.
